UNITED STATES PATENT OFFICE.

JOSEPH SEXTON THOMPSON, OF MILL VALLEY, CALIFORNIA.

ELECTRICALLY-HEATED STEAM-RADIATOR.

1,037,369.

Specification of Letters Patent.

Patented Sept. 3, 1912.

Application filed March 12, 1912. Serial No. 683,315.

To all whom it may concern:

Be it known that I, JOSEPH S. THOMPSON, a citizen of the United States, residing in Mill Valley, in the county of Marin and 5 State of California, have invented a new and useful Improvement in Electrically-Heated Steam-Radiators, of which the following is a specification.

My invention relates to means for generating steam for the purpose of heating a steam radiator and includes means for generating the steam and means for automatically regulating the amount generated, and for automatically varying the amount of 15 current consumed and for automatically discontinuing all flow of current, should the temperature of the air surrounding the radiator be such as to permit steam pressure to result from the generation of steam at a 20 rate faster than that at which the radiator condenses it. I attain this object by the device illustrated in the accompanying drawing in which—

Figure 1 is a side elevation of my device 25 attached to an ordinary radiator. Fig. 2 is a vertical cross section of the steam generator. Fig. 3 is a sectional plan view on line 3—3 of Fig. 2, showing the carbon electrodes D'. Fig. 4 is a sectional plan view 30 on line 4—4 of Fig. 2 showing the carbon electrodes D. Fig. 5 is an elevation to further illustrate the stirrup O and ball P.

Similar letters refer to similar parts throughout the several views.

35 A is an ordinary radiator designed for hot water heating systems and B is a return pipe connecting the generator C with the farther end of the radiator A.

Part C is a case or container of the generator. Parts D are carbon electrodes supplied with current from the electrical connection E. Parts D' are carbon electrodes supplied from the electrical connection E'. These electrical connections and carbon 45 electrodes are supported by and insulated from part F, which forms the lower cover of the case C. They are also insulated from the case C by the rubber insulation G.

When water is supplied in the case C, to 50 sufficient degree to submerge the carbons D and D', or any of them, current will flow from one carbon to another with the effect of heating the water, and should sufficient water be supplied through the aperture H, 55 and following the path of the arrows, be free to return to the radiator at the aperture

J there would be continuous circulation of heated water flowing through the generator into the radiator and back by the return pipe, B. This water would in time be heated to the point where it would give off steam into the portion above the water level, which is shown by the dotted line in Fig. 1.

Should the steam accumulate faster than the surrounding temperature would cause 60 it to condense in the radiator, a steam pressure develops and this pressure acts on the diaphragm K, tending to raise it against the spring N, the pressure of which is regulated by screw M. Under pressure of the steam, 65 the diaphragm K raises the stirrup piece O, which carries the ball P, which is so placed that it is possible for it, when raised sufficiently high, to close the aperture Q, cutting off the circulation of the water. When- 70 ever circulation is checked, the steam generated forces the water back into the pipe B and current ceases to flow until the steam pressure in the generator C drops to the 75 point where the water is permitted to rise 80 and again submerge the two lower electrodes in the sets D and D'. Whenever the flow of current is again established, steam is again generated and the process is repeated.

In actual operation the diaphragm K 85 rarely causes the ball P to entirely close the aperture Q, and as a result, the flow of water and steam, instead of being stopped, is partly restricted, and thus the heater automatically holds such steam pressure in the 90 radiator as is pre-determined by the setting of the screw M, with a comparatively steady 95 flow of current.

Part R is an ordinary globe valve which is used in connection with the funnel S for 95 filling the generator and radiator.

What I claim is:

1. In an electric water heater, the combination of a vessel adapted to contain water, supplied through an aperture in its 100 bottom, a plurality of electrodes arranged in the vessel, a ball valve above the electrodes, and a diaphragm operating said ball valve, which ball valve and diaphragm regulate the amount of water submerging the electrodes.

2. In an electric heater, the combination of a vessel having an insulating lining and a lower and upper aperture, adapted to contain water to be heated by electrodes insulated from the vessel and so arranged that the water can flow around and between 110

them, provided with a ball valve, and a diaphragm operating to control the submerging of the electrodes by throttling the upper aperture, all substantially as described.

3. In an electric water heating apparatus, in combination with a boiler or chamber, a plurality of electrodes inclosed therein, and insulated from the boiler or chamber, a ball valve set above said electrodes, a diaphragm operating said ball valve, a spiral spring tending to counteract the diaphragm and holding the ball valve open, and a thumb screw operating to adjust the compression of said spring.

4. In an electric water heating apparatus, in combination with a boiler or chamber having insulated walls and a plurality of carbon electrodes, means for conducting electric current to said electrodes, and a dia-

phragm operated ball valve regulating the supply of water submerging the electrodes.

5. In an electric water heating apparatus, the combination of a chamber, having insulated walls, a diaphragm operated ball valve in the upper portion of said chamber, a plurality of carbon electrodes in the lower portion of said chamber, means for electrically energizing the carbon electrodes, an aperture at the bottom of the chamber for supplying water to be heated, and an outlet aperture at the top of the chamber, controlled by the diaphragm operated ball valve.

In witness whereof, I have hereunto set my hand this 5th day of February 1912.

JOSEPH SEXTON THOMPSON.
